[57] CLAIM

The ornamental design for a funnel lid for trash container, as shown and described.

DESCRIPTION

FIG. 1 is a top left front perspective view of a funnel lid for trash container showing my new design;

FIG. 2 is a front elevational view thereof; the rear elevational view being a mirror image;

FIG. 3 is a right side elevational view thereof; the opposite side being a mirror image;

FIG. 4 is a top plan view thereof;

FIG. 5 is a bottom plan view thereof;

FIG. 6 is a top, left and front perspective view of a second embodiment of the funnel lid for trash container;

FIG. 7 is a front elevational view of FIG. 6, the rear elevational view being a mirror image;

FIG. 8 is a side elevational view of FIG. 6, the opposite side view being a mirror image;

FIG. 9 is a top plan view of FIG. 6; and,

FIG. 10 is a bottom plan view of FIG. 6.
